UNITED STATES PATENT OFFICE

ADOLPH G. KUPETZ, OF NEW YORK, N. Y., ASSIGNOR TO UNDERWOOD ELLIOTT FISHER COMPANY, OF NEW YORK, N. Y., A CORPORATION OF DELAWARE

TYPEWRITING MACHINE

Application filed March 15, 1928. Serial No. 261,751.

This invention relates generally to typewriting machines, and more particularly to means for counting the number of items, such, for example, as the credits and debits 5 typed on a series of statement-sheets or the like.

To make a count of the number of debit items appearing on customer statement-sheets each month, the counting mechanism 10 is sometimes used only for a few days in each month.

It is an object of the present invention to provide, in a typewriting machine, an improved item-counting mechanism operatively connected to the carriages, which connection can be easily and quickly released, and the mechanism locked in ineffective condition until needed again.

Heretofore, item-counting devices operated by movement of a typewriter-carriage 20 could not be quickly and conveniently adjusted for use with statement-sheets of varying widths. It is a further object of the present invention to provide an item-counting mechanism which can be adjusted quickly and easily for use with different widths of work-sheets.

In the embodiment of the present invention illustrated in the drawings, a register 30 is fastened on the side of the main frame of an Underwood combined typewriting and computing machine, and mechanism operatively connected to the register is slidably mounted on the rear side of the main frame, 35 so as to be effectively engaged upon return of the carriage by a column-stop adjustably mounted on the usual lateral rack-bar of the tabulating mechanism of the machine. In using my invention for counting debit items 40 on a series of statement-sheets, the stop is manually set in relation to the debit-column zone of the platen, so that upon line-spacing the debit column of each statement-sheet past the printing point the column-stop is moved 45 over a tooth on the slidably-mounted register-operating mechanism, the latter being affected idly by the stop as it moves leftwardly past the tooth. Upon return of the carriage to the right, as usual, for typing 50 another item in the debit column or for re-

moving the statement-sheet, the stop operatively engages the tooth and slides the register-operating mechanism to the right a distance sufficient to run one unit into the register. At that point the slidably-mounted 55 mechanism automatically disengages itself from the stop and is returned by a spring to normal position.

To render the item-counting mechanism ineffective when not needed, it includes a 60 linkage which carries the stop-engaging tooth, and means are provided for swinging the linkage down to move the tooth out of the path of the stop. A releasable lock is arranged for automatically locking the linkage 65 in its ineffective position. The present invention can also be used as a line-counter by properly positioning the stop on the rack-bar.

A feature of the present invention resides 70 in the provision of means for yieldingly bracing a joint of the tooth-carrying linkage, whereby the latter may be slid laterally as one stiff member for register-operating purposes, yet being swingable downwardly at 75 the connection between the links to remove the tooth from the path of the stop.

Another feature resides in mounting the tooth-carrying, register-operating linkage on the rear of the main frame adjacent the usual 80 rack-bar of the tabulating mechanism, so that a usual, manually adjustable stop on the rack-bar may serve for engaging the tooth of the item-counting mechanism.

Other features and advantages will hereinafter appear.

In the accompanying drawings,

Figure 1 is a fragmentary, front elevational view of an Underwood combined typewriting and computing machine having my invention applied thereto. A statement-sheet is shown in position in the machine for having debit items counted as they are typed on the statement-sheet.

Figure 2 is a fragmentary, front view of 95 the item-counting mechanism showing it at the end of its operative movement to the right, as it is being released to be returned to normal position.

Figure 3 is a fragmentary, front view of 100

the item-counting mechanism illustrating how it is moved idly as the carriage is letter-spaced to the left upon typing an item.

Figure 4 is a fragmentary, front view of certain parts of the item-counting mechanism illustrating how it is disposed in ineffective position.

Figure 5 is a fragmentary, rear perspective view of an Underwood combined typewriting and computing machine having the item-counting mechanism of my invention applied thereto.

Figure 6 is a fragmentary, side view of the structure shown in Figure 5.

Figure 7 is a view illustrating how certain parts of the item-counting mechanism may be applied to the typewriting machine shown in Figure 5, without interference with the tabulating mechanism of the machine.

The present invention is illustrated as applied to an Underwood combined typewriting and computing machine, in which types 10 strike against a platen 11 mounted on a shaft 12 journaled in a platen-frame 13 which is mounted on a carriage 14 movable laterally on a front rail, not shown, and a rear carriage rail 15. The carriage rails may be fastened rigidly on a main frame generally designated as 16. Upon striking any one of a plurality of keys 17 the type 10 associated with the operated key is swung against the platen 11 by interponents, not shown, and the carriage 14 is letter-spaced one step to the left by usual letter-spacing mechanism, not shown. For quickly moving the carriage leftwardly to bring a desired portion of a statement sheet 20 to the printing field, the machine may have a tabulating mechanism including a rack-bar 21 fastened on the carriage 14 to be movable therewith, column-stops 22 adjustably secured on the rack-bar, and a stop rod 23 movable into the path of the column-stops 22 by instrumentalities not shown. The construction of the column-stop 22 may be substantially like the column-stop disclosed in Patent No. 1,649,329 to O. Thieme, dated November 15, 1927, and may be made from the last-named stop by cutting a short portion off its forward end. The other parts described hereinbefore may be like those in an Underwood typing and computing machine.

In some business offices, it is required to count certain items, such as debits and credits, which appear on statement sheets. All of the statement sheets 20 of a series are usually the same width and all debit columns 24 or credit columns 25 thereon can be brought successively to the same position on the platen of a typewriter by laterally gaging the statement sheets to a usual side-edge gage 26 on a rear paper-table 27.

In carrying out the present invention, mechanism is provided which is made effective for counting a debit item, for example,

by bringing the debit column to the printing point and, after typing the debit, returning the carriage to the right in the usual way. This counting mechanism includes a register 28 fastened by screws 29 to the main frame 16 at the left side thereof. An upwardly extending crank-arm 30 which is fastened on a main shaft 31 of the register 28 carries a forwardly extending pin 32 fast in its upper end. An actuator generally designated as 33 has right and left, inreaching sheet-metal slide or link members 34 and 35, respectively, each having a rectangular cross-section, the long side of which is disposed in a vertical plane. The inner or inreaching ends of the link members are pivotally fastened together or hinged by a horizontal screw 36.

In operative position (Figure 1) the inner portions of the links 34 and 35 are horizontally disposed, and their outer end portions are inclined downwardly at an angle of approximately 45 degrees and then extend horizontally except as noted hereinafter. Each link has a cam slot 37 in its outer end portion. The right-hand portion of each slot is normally horizontal and the left-hand portion, which is considerably shorter than the right-hand portion, is inclined upwardly at an angle that will permit the left-hand slot portion of the link 34 to be centrally disposed in the downwardly inclined end portion of the link, the inclined portions of each slot being parallel. Each slot engages about a shoulder screw 38 threaded in a usual integral standard 39 disposed at the sides of the main frame 16 for supporting the carriage rail 15. A tensile spring 40, which has one end fastened to a pin 41 in the main frame 16 and the other end to a pin 42 in a depending ear 43 on the link 34 adjacent its outer end, is effective to normally hold the actuator 33 in its normal position wherein the right-hand ends of the slots 37 are disposed against the screws 38.

To hold the inner, pivotally-connected ends of the links 34 and 35 in normal horizontal position against the action of gravity, and against the turning force of the spring 40, a depending integral ear 44 is provided on each of the links 34 and 35 adjacent the pivot screw 36, the ears being positioned on opposite sides of the screw. To each ear 44 is fastened the end of the tensile spring 45 having a small amount of initial tension. Also, depending integral lugs 46 and 47 are provided on the inner ends of the links 34 and 35 respectively. The lug 46 is disposed on the opposite side of the screw 36 from the main body portion of the link 34, and the lug 47 is disposed in like manner on the opposite side of the screw from the link 35. The lugs 46 and 47 are positioned between the ears 44 and are bent forwardly and rearwardly respectively to engage closely against the lower edges of the links 35 and 34 respectively. Each lug engages under the link which car-

ries the other lug between the pivot screw 36 and the main body portion of the link (Figures 2 and 3), thereby preventing upward movement of the pivotally connected, in-reaching ends of the links 34 and 35. The above-described organization including the spring 45, ears 44 and lugs 46 and 47 serves to stiffen or brace the pivotal connection of the links 34 and 35 whereby they may be moved endwise or downward as one piece, without angular movement, relative to each other about the pivotal connecting screw 36. Moreover, the inner ends of the links may be swung downward for a purpose to presently appear.

The link 35 has an enlarged outer end including a triangular-shaped depending portion 50 in which is cut a vertically disposed slot 51 which has a lower open end and engages about the pin 32 in the crank-arm 30. In the normal position of the register 28, which may be of the usual ratchet type, the arm 30 is inclined to the left (Figure 1), and to operate the register it is only necessary to slide the actuator 33 to the right. According to the present invention, instrumentalities for doing this may include an up-reaching integral tooth 52 on the inner or right hand of the link 35. The left-hand edge 53 of the tooth is vertical and the right-hand edge 54 slopes downwardly to the right. A counting or actuating stop 55, which may be constructed like the stop shown in the above-mentioned patent to Thieme, has a forward end portion 56 which extends across the plane of the tooth 52. The stop is adjustably mounted on the rack-bar 21. Then when the carriage 14 is line-spaced leftwardly in bringing the debit column 24 into the printing field, the forward end of a depending flange element 57 of the stop 55 comes against the right-hand sloping edge of the tooth 52 and presses it and the inner ends of the links 34 and 35 down, the spring 45 yielding and permitting easy depression of the links. The register 28 is not affected by this movement of the links since the slotted end portion 50 of the link 35 is swung upward about the left-hand screw 38 and idly affects the pin 32 and arm 30. After the stop 55 moves past the tooth 52 the latter swings up to normal position without affecting the register. When the proper debit has been typed in the debit column 24 the carriage will be returned to the right as usual, preparatory to typing another debit, and the platen may be line-spaced by usual line-spacing devices including a ratchet-wheel 58 or by rotation of a usual finger-wheel 59 fast on the platen shaft 12. If only one debit is to be typed on the statement sheet, the carriage will be returned, as usual, for conveniently removing the statement sheet and inserting another. Upon moving the carriage rightwardly the flange element 57 abuts squarely against the

left-hand edge 53 of the tooth 52 and moves the actuator 33, including the link 35, rightward with it a distance sufficient to swing the pin 32 in the slot 51 clockwise an amount that will cause one unit to be run into the register. When the links have nearly moved the distance required to operate the register, the inclined portions of the slots 37 will have reached the screws 38 and thereafter the co-active cam action of the slots and screws will cause the links 34 and 35 to begin to be moved downwardly. A short additional lateral movement of the actuator will disengage the tooth 52 from the stop 55 (Figure 2) and the spring 40 will then be effective to return the actuator to starting position.

It can readily be seen that a typed item on a statement-sheet or the like can be counted by the above-described organization of parts without appreciably increasing the force necessary to return the carriage and without noticeably affecting the lightness of touch of the keys.

Since a combined typewriting and computing machine is used for various kinds of work, it is desirable, at times, to disable or release the item-counting mechanism of the present invention and secure it in its released condition until needed again. To this end, means are provided in the present invention for swinging the link 35 down to bring the tooth 52 out of the path of the stop 55 and for latching the tooth in ineffective position. A depending link 61 is pivotally fastened by a screw 62 to the link 35 at a point intermediate the left-hand shoulder screw 38 and the screw 36. The lower end of the link is constructed with a lengthwise slot 63 for a purpose to presently appear. This slotted lower end engages loosely about a shoulder screw 64 whose threaded end extends forwardly to engage in a tapped hole in a laterally extending tab 65 on the rear end of an arm 66 of a bell-crank 67, which is pivoted about a stud 68 in a bracket arm 70 fastened to the left side of the main frame 16, a downwardly extending open slot 71 in the bell-crank being arranged to engage about the stud. The arm 66 may have a bend 72 and a bend 73 to space the tab 65 far enough away from the screw 38 to permit easy operation of the disabled means. The bell-crank 67 has an upwardly extending arm 74 to which is integrally joined a forward-reaching extension 75 which is bent leftwardly at 76 and forwardly at 77. The leftward bend 76 is made to bring an extreme forward end portion 78 of the arm 74 substantially in line with the center of a usual left-hand front post or column element 79 of the main frame 16. To the end portion 78 is pivotally fastened a link 80 of rectangular cross-section, which extends forwardly through holes 81 in usual in-reaching flange portions 82 of the post element 79 and ter-

minates a short distance forwardly from the latter in a cylindrical portion 83 which is constructed to slide with a loose fit in the holes 81. A push-button 84 may be fastened on the forward end of the link 80. It can readily be seen by an inspection of Figures 4, 5 and 6 that a light push rearwardly on the button 84 will be effective to swing the link 85 downwardly about the left-hand shoulder screw 38, and will move the tooth 52 downwardly out of the path of the stop 55. The extent of the downward movement of the tooth is limited by a screw 85 in the bracket 70 striking against the rear end of an elongated slot 86 cut in the arm 74 above the pivot stud 68.

It is desirable to have means for automatically locking the tooth 52 in its ineffective position when moved thereto by operation of the push-button 84. To this end, a notch 88 is provided in the lower edge of the link 80. A mounting plate 89 is fastened against the rear face of the post 79 by devices including an integral hook-like member 90 which extends forward and engages around the right edge of the rear-flange portion 82 of the post 79. At the lower end of the plate an integral ear 91 is bent forward to lie against the outer face of the post 79 and a screw 92 passes through a hole in the ear and is threaded into the post. A locking bolt or trigger 93 is pivotally fastened by a shoulder screw 94 to the plate 89 below the link 80. A small rectangular piece is cut out of the upper end 35 portion of the bolt 93 on the right-hand side thereof (viewed from the front), thus leaving an upwardly extending finger element 95 on the left side for a purpose to presently appear. The upper portion of the bolt 93 is normally pressed lightly against the link 80 by a leaf spring 96 mounted on a rearwardly-extending integral ear 97 of the mounting plate 89, the spring pressing lightly against the lower end of the bolt. Only a short section 40 of the right edge of the upper end portion of the bolt 93 engages against the lower edge portion of the link 80, and consequently when the link is pushed a sufficient distance to the rear the notch 88 moves opposite to the bolt 93 and permits the spring 96 to swing the upper end of the bolt to the right through the notch. The finger 95 is effective to limit the rightward movement of the bolt by the spring 45 and co-operates with the latter to hold the trigger in effective position.

The upper end of the trigger 93 may be swung out of locking engagement with the link 80 by pressing rightwardly on a finger piece 98 which is integrally joined to the lower end of the bolt and extends therefrom to the left a short distance past the left face of the post 79 and has a knurled tab 99 bent forwardly to be conveniently pressed by a finger of the operator.

It will be noted that provision of the slot

63 and the link 61 (Figure 2) permits the tooth 52 to be pressed down out of the way of the stop 55 without moving the push-button 84 at the front of the carriage. It will be seen on inspection of Figure 7 that, while the links 34 and 35 are spaced from the rear face of the standards 39 by friction-reducing washers 100, the links do not interfere with the movement of the column stops 22, and neither do the latter affect the item-counting mechanism regardless of their position on the rack-bar 21. It can be further seen that the stop 55 may be variably positioned on the rack-bar for co-operation with the tooth 52 for counting items in columns on work-sheets of various widths, or for counting lines on a work-sheet.

It will be noted that the mechanism provided in the present invention for operating a register can be advantageously used with any form of register, making it possible to employ a variety of standard registers.

It can be readily seen by those skilled in the art that the present invention which is disclosed as applied to an Underwood combined typewriting and computing machine can be easily applied by a skilled mechanic to typewriting machines of other makes which have stationary main frames and laterally movable carriages.

Variations may be resorted to within the scope of the invention, and portions of the improvements may be used without others.

Having thus described my invention, I claim:

1. In a typewriting machine, the combination with a main frame, a laterally movable carriage having a platen, around which may be fed a succession of like statement-sheets, means for laterally guiding columns on said statement-sheets around the same portion of said platen, and a lateral rack-bar on said carriage, of means for counting the items typed on said statement-sheets in said columns, including a register fastened on a side of said main frame, a stop on said rack-bar, mechanism including links slidably mounted on the rear of said main frame and operatively connected to said register and positioned to be operatively engaged by said stop, upon return of said stop to the right subsequently to the typing of an item, whereby to operate said register and count said item, means for moving said mechanism to ineffective position, so that it will not be engaged by said stop, and a releasable lock for locking said mechanism in said ineffective position when said mechanism is not being used.

2. In a typewriting machine having a platen around which may be fed a succession of statement-sheets and a side-edge gage for positioning said statement-sheets laterally, the combination with a main frame on said machine, a laterally-movable carriage supporting said platen, and a rack-bar on said

carriage in the rear of said main frame, of a register fastened on a side of said frame, a laterally adjustable stop on said rack-bar, a linkage including two pivotally-connected, inreaching links slidably mounted on the back of said main frame adjacent said stop, a tooth on said linkage adjacent the connection of said links, said tooth having a sloping right-hand side and a substantially vertical left-hand side, means for yieldingly bracing said pivotal connection of said links to hold said tooth normally in the path of said stop, whereby said stop may press said tooth down and move said linkage idly upon movement 10 of the carriage to the left, said bracing also being effective to hold said linkage up against gravity in operative position, so that when said stop engages the left side of said tooth upon movement of the carriage to the 20 right the linkage is moved as a stiff member with the carriage to operate said register, means for automatically disengaging said tooth from said stop when said linkage has been moved laterally a distance sufficient to 25 operate said register, and means for bringing said linkage back to normal starting position.

3. In a typewriting machine, in combination, a main frame, a carriage, a register mounted on said frame, a linkage operatively connected to said register, said linkage including two laterally-disposed links pivotally fastened to each other intermediate the sides of said frame, each of said links having a lengthwise cam-slot therein adjacent its outer end, screws in said frame for engaging through each of said cam-slots, a releasable operative connection between said carriage and said linkage adjacent the pivotal connection of said links, and yielding means for bracing said pivotal connection which is effective for holding said linkage normally rigid, whereby said linkage may be moved laterally with said carriage as a stiff member for operating said register, said screws and said cam-slots cooperating upon lateral movement of the stiffened linkage to move the latter away from said carriage, so as to release the connection between it and said linkage immediately after the operation of said register.

4. The structure described in claim 3 characterized by said bracing means having a tensile spring, each end of which is fastened 55 to each link on opposite sides of said connection and below the latter, and a lug on each link on opposite sides of said connection, the lug on each link being bent for engaging closely under the other link.

60 5. In a typewriting machine, a yieldingly braced pivotal connection for two links of a linkage for normally holding said linkage as one stiff member, said connection including a pivot-pin fastening the ends of said links 65 together, a tensile spring having one end fas-

tended to an ear on each link at opposite sides of said pin, and a lug on one link bent for engaging closely against the edge of the other link on the same side of said pin as said spring.

70

6. In a typewriting machine, in combination, a main frame, a carriage, a register fastened on a side of said main frame, a linkage slidably mounted on said main frame and operatively connected to said register, a tooth 75 on one of the members of said linkage arranged to be engaged by said carriage, means for holding the members of said linkage in substantially horizontal alignment while said tooth is engaged by said carriage, whereby 80 said linkage may be slid for operating said register, means effective for automatically disengaging said tooth from said carriage upon operation of said register, and means for returning said linkage to normal starting 85 position after it is disengaged from said carriage.

7. The structure described in claim 6, characterized by means for holding the members of said linkage in horizontal alignment while 90 it is being returned to normal starting position.

8. In a typewriting machine, the combination with a main frame and a carriage having a lateral rack-bar disposed in the rear 95 of said frame, of a register mounted on said frame at one side thereof, a laterally-disposed linkage slidably mounted on the rear side of said main frame and operatively connected to said register, a stop mounted on said rack-bar and extending forwardly, whereby the path of its forward end portion will lie in the plane of said linkage, a tooth carried by said linkage projecting into the path of said stop, whereby a predetermined lateral movement of said carriage is effective to operate said register, and means for swinging said linkage in a vertical plane to move said tooth out of the path of said stop, so that said carriage may be returned without 100 affecting said register.

9. The structure described in claim 8, characterized by manually-operable means for moving said linkage instrumentalities to a position, whereby said tooth is removed from the path of said stop, and automatically operating means for latching said manually-operable means in operated position.
